[57] **CLAIM**

The ornamental design for a wheel for guiding a ladder against a structure, as shown and described.

DESCRIPTION

FIG. 1 is a front, top and side perspective view of the wheel for guiding a ladder against a structure embodying the design of the present invention;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof, the bottom view being a mirror image of the top view shown in FIG. 6.

FIG. 1

FIG. 2

FIG. 3

FIG. 4

FIG. 5

FIG. 6
